Primary Examiner — Vy N Koenig

CLAIM

The ornamental design for a combined rollable screen, remote and remote container with a hook, as shown and described.

DESCRIPTION

FIG. 1 is a front, top perspective view of combined rollable screen, remote and remote container with a hook showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded perspective view of the combined rollable screen, remote and remote container with a hook, in which the broken line screen and remote portion of the figure drawings is included to show unclaimed subject matter only and forms no part of the claimed design.

1 Claim, 8 Drawing Sheets
